[57] CLAIM

The ornamental design for a control panel face plate for a beverage dispenser valve, as shown and described.

DESCRIPTION

FIG. 1 is a front, bottom, right side perspective view of a control panel face plate for a beverage dispenser valve, showing our new design;

FIG. 2 is a right side elevational view thereof;

FIG. 3 is a front elevational view thereof;

FIG. 4 is a top plan view thereof;

FIG. 5 is a bottom plan view thereof; and

FIG. 6 is a left side elevational view thereof.

The broken line showing of the dispenser valve is for illustrative purposes only and forms no part of the claimed design. The rear view not shown is of conventional appearance.
